FIG. 1 is a front perspective view showing my new design.
FIG. 2 is a front elevation view thereof, the clip holder being
shown as mounted to a fragmentary vertical mounting
surface with a pair of threaded fastener to illustrate environ-
ment, the mounting surface and the outer diameter of the
fasteners being shown in dashed lines and forming no part
of the claimed design.

FIG. 3 is a right side view thereof, the left side view being
a mirror image thereof.

FIG. 4 is a top plan view;

FIG. 5 is a bottom plan view; and,

FIG. 6 is a rear elevation view thereof.
